(No Model.)

P. STEVES.

DEVICE FOR OPERATING THE DOORS OF MINE SHAFTS.

No. 373,105.

Patented Nov. 15, 1887.

UNITED STATES PATENT OFFICE.

PARKER STEVES, OF ASPEN, COLORADO.

DEVICE FOR OPERATING THE DOORS OF MINE-SHAFTS.

SPECIFICATION forming part of Letters Patent No. 373,105, dated November 15, 1887.

Application filed April 29, 1887. Serial No. 236,601. (No model.)

To all whom it may concern:

Be it known that I, PARKER STEVES, a citizen of the United States, residing at Aspen, in the county of Pitkin and State of Colorado, 5 have invented a new and useful Improvement in Devices for Operating the Doors of Mine-Shafts, of which the following is a specification.

My invention relates to an improvement in devices for operating the doors of mine-shafts; 10 and it consists in the peculiar construction and combination of devices, that will be more fully set forth hereinafter, and particularly pointed out in the claims.

In the drawings, Figure 1 is an elevation of 15 an apparatus embodying my improvements, showing the doors closed. Fig. 2 is a similar view of the same, showing the doors open. Fig. 3 is a top plan view of Fig. 2. Fig. 4 is a detail view of one of the connecting-links.

20 A represents a platform, which is erected on one side of the mine-shaft. B represents the casing of the shaft, and C represents the doors, which are hinged at their outer sides and close together at their free edges, so as to close the 25 shaft.

D represents the frame, which is triangular in end elevation, and which supports the doors when the latter are closed.

To one end of the frame D is attached a pair 30 of vertical guide-rods, E, which extend down through the platform for a suitable distance.

F represents a cross-head, which slides vertically on the guide-rod, and is provided with downward-extending tubular sleeves G, which 35 work on the guide-rods. The central portion of the cross-head is arched, as shown, and from the upper side of the arch depends an eye-bolt, H.

Each of the doors C is provided on its inner 40 side, at one end, with a bracket-plate, I.

K represents a pair of links, which connect the ends of the cross-head F to the ears of the bracket-plates I. Each link is composed of a right-hand screw, K', the left-hand screw L, 45 and a sleeve, M, which is interiorly threaded and adapted to receive the inner ends of the screws in order to connect the same together. By turning the sleeve in one direction it will be understood that the screws will be moved 50 from each other, thereby lengthening the link, and by turning the sleeve in the contrary direction the screws will be drawn toward each

other and thereby shorten the link. By thus making the links longitudinally adjustable they are adapted to be so adjusted as to cause 55 the doors to fit snugly together and upon the frame D when they are closed, so as to effectually close the shaft.

N represents a bell crank-lever, which is fulcrumed between a pair of knees or standards, 60 O, that are bolted on the platform A. This bell-crank lever has a short arm, P, and a long arm, R. The outer end of the short arm is pivoted to the lower end of a connecting-rod, S, and the upper end of the said connecting- 65 rod is pivoted to the eye of the bolt H by means of a bolt, T, and thereby connected to the cross-head.

U represents a foot-lever, which is fulcrumed on the same bolt or pin with the bell-crank 70 lever, the latter being provided with an opening at its fulcrum to receive the foot-lever, and the short arm of the said foot-lever is adapted to bear under the short arm P of the bell-crank lever, for the purpose to be herein- 75 after explained.

V represents a vertical segment-plate, which is bolted on the platform A, and bears against one side of the bell-crank lever. The said segment-plate has a notch, W, formed in its 80 upper edge at a suitable point.

X represents a spring-actuated locking-bolt, with which the long arm of the bell-crank lever is provided. The said locking-bolt is adapted to engage the notch W, and is operated by a handle, Y, which is fulcrumed to the long arm of the bell-crank lever, near the upper end thereof.

The operation of my invention is as follows: When the upper end of the bell-crank lever is 90 turned to the right, the short arm thereof draws downward on the connecting-rod T and causes the cross-head F to descend on the guide-rods, and as the cross-head is connected to the door C by means of the links K, it follows that the 95 said doors are caused to close together and on the upper inclined sides of the frame D. When the upper end of the bell-crank lever is moved to the left, the cross-head is caused to rise and thereby force the doors apart and 100 open the same, and by the time that the long arm of the bell-crank lever has assumed a position alongside the notch W the spring-actuated bolt X drops into the said notch, and

thereby locks the bell-crank lever to the segment-plate, and consequently locks the doors in an open position, as shown in Fig. 2. The foot-lever serves to aid the operator in moving the bell-crank lever, as it enables the operator to stand upon the outer end of the foot-lever, thus causing his weight to be utilized in assisting to work the lever.

Having thus described my invention, I claim—

1. The combination of the doors C, hinged at their outer sides and adapted to close together, the vertically-movable cross-head, the links connecting the cross-head to the doors, and the lever to operate the cross-head and thereby open and close the doors, substantially as described.
2. The combination of the frame D, the doors C, hinged thereto at their outer sides, the vertically-movable cross-head F, longitudinally-adjustable links connecting the said cross-head to the door, and the lever to raise and lower the cross-head and thereby open and close the doors, substantially as described.

3. The combination of the frame D, the doors C, hinged thereto at their outer sides and adapted to close together, the vertically-movable cross-head, the links connecting the same to the door, the bell-crank lever connected to the cross-head, and devices, substantially as set forth, to lock the lever when the doors are opened, substantially as described.

4. In combination with the hinged doors C, the guide-rods, the cross-head moving on the guide-rods and having depending tubes to slide over the rods, the links connecting the cross-head to the doors, and the operating-lever, as set forth.

In testimony that I claim the foregoing as my own I have hereto affixed my signature in presence of two witnesses.

PARKER STEVES.

Witnesses:

CHARLIE PETERSON,

DANIEL A. BREESE.
